UNITED STATES PATENT OFFICE

164,874

COMB

Livia Mitchell, New York, N. Y.

Application August 2, 1950, Serial No. 11,537

Term of patent 14 years

(Cl. D86—8)

To all whom it may concern:

Be it known that I, Livia Mitchell, a citizen of United States of America, residing at New York, in the county of New York and State of New York, have invented a new, original, and ornamental Design for a Comb, of which the following is a specification, reference being had to the accompanying drawing, forming part thereof.

In the drawing:

Fig. 1 is a front face view of a comb showing my new design; and Fig. 2 is a top plan view of a comb according to Fig. 1.

The characteristic feature of my design resides in the combination of a concave oval-shaped side comb having spring teeth of graduated size extending from the long center tooth to each of the sides, and the tips and bases of the teeth disposed along an oval configuration, said comb having a proportionate overhang of a thickened back to complete the curvature of the toothed body, all as shown.

I claim:

The ornamental design for a comb, as shown and described.

LIVIA MITCHELL.
